UNITED STATES PATENT OFFICE.

WEBSTER L. MARBLE, OF GLADSTONE, MICHIGAN.

FOLDING COMPOUND TOOL.

1,036,664.

Specification of Letters Patent. Patented Aug. 27, 1912.

Application filed October 2, 1911. Serial No. 552,461.

To all whom it may concern.

Be it known that I, WEBSTER L. MARBLE, a citizen of the United States, residing at Gladstone, county of Delta, and State of Michigan, have invented certain new and useful Improvements in Folding Compound Tools, of which the following is a specification.

This invention relates to folding compound tools.

The invention has for its object the provision of a tool of the character set forth wherein the plurality of tools which may be a screw-driver, knife blade, reamer, chisel, file, bradawl, or of other character are combined with a novel articulated handle into which they are adapted to collapse and by which they are held in neat, compact, and handy arrangement.

20 A further object is to provide, a tool of the character set forth, provided with a novel supplemental foldable handle enabling the user to obtain a firm grip, and particularly adapting the device for easy manipulation where the tools are of relatively large size but without making the device cumbersome or detracting from its neatness and compactness.

30 Another object is the provision of a one-piece handle construction, enabling the device to be inexpensively manufactured and at the same time giving strength, durability, and compactness.

35 A still further object is the provision, in a tool of the character set forth, of a new joint between the parts of the folding or collapsible handle thereof, and an additional object is to provide a pivotal connection for the tools carried by the handle 40 which will permit removal of the tools with facility and render the use of interchangeable tools a convenient matter.

45 Another object is to provide the implements of a compound tool with wrench openings arranged for alinement in a new manner.

50 The invention is susceptible of modification and but two of the principal embodiments thereof are disclosed and set forth fully hereinafter and disclosed in the accompanying drawings, in which:—

55 Figure 1 is a perspective of the tool closed; Fig. 2, a perspective showing the clasp thrown back and one of the screw-drivers being opened; Fig. 3, a perspective

view showing the clasp closed and a screw-driver ready for use; Fig. 4, a longitudinal section, broken away, showing the parts folded; Fig. 5, a cross-section on line 5—5, Fig. 4; Fig. 6, a plan partly sectional of the 60 clasp detached, dotted lines showing how the arms are swung back for connection to the pivot; Fig. 7, a cross-section through the fastening screw, when the tool is closed; Fig. 8, a view of the pivot; Fig. 9, a perspective of a modification, closed; Fig. 10, a similar view with a tool and the supplemental handle extended; Fig. 11, a longitudinal section; Fig. 12, a face view with the clasp thrown back and the tools opened 70 out; and Fig. 13, a cross-section through the pivot.

The handle consists of a holder 1 and a clasp or lock 2. The section 1 is formed of a single piece of metal, preferably steel, 75 bent back upon itself with its parts in spaced arrangement and joined at their free ends by headed male and female screws 3 and 4 (Fig. 7) on which the tools 5, 6, 7 are loosely pivoted, said tools at the shorter 80 ends being of substantially the same width as the holder 1 so that when the clasp 2 is clasped, they will be firmly held against any lateral movement or wobbling, and for this purpose the clasp 2 has its sides 8 of approximately the same distance apart as the width of the holder 1 and the short ends of the tools, the clasp being provided with a bridge or web 9 to limit its closing movement by abutting the holder 1. 90

The tools may be of any desired character. All may be screw-drivers having ends of different sizes, or, a screw-driver may be combined with a knife blade or with a chisel, file, reamer, bradawl, etc., the assortment of 95 tools being according to the fancy. The male and female screws 3 and 4 prevent any loosening thereof, but at the same time permit quick and easy separation and the removal of any of the tools and the substitution of others whenever desired, thus making the tools interchangeable. The butt ends of the tools 5, 6, 7 are provided with wrench openings 6^a which, when alined while the tools are locked by the handle, 105 constitute an efficient wrench particularly adapted for use by automobile owners as a gas tank wrench.

In the form of the invention shown in Figs. 1 to 8, one kind of a pivotal connec- 110

tion is used between the holder 1 and clasp 2, and in the form shown in Figs. 9 to 13, a modification thereof is provided, the latter being particularly adapted for use on the 5 larger grades of the article and the former on the smaller grades thereof. In each form, however, the holder 1 is formed of a single piece of metal and the clasp 2 is made in one piece.

- 10 Referring first to Figs. 1 to 8, here the arms 8 are springy or resilient and provided with apertures 10. There is provided a pivot 11 having gudgeons 12 which project beyond the holder 1 and each adapted to 15 pass into the apertures 10 on springing the arms 8 to permit this connection being effected. This connection permits the ready detachment of the handle and the clasp and the easy assembly thereof, thus rendering 20 the device cheap of manufacture. The pivot 11 has a peripheral groove 13 which receives a struck-up nib or a suitable projection on the holder 1, whereby the pivot is retained in the holder 1 at all times. 25 This, also, enables the cost of manufacture to be minimized.

Referring to Figs. 9 to 13, representing a larger grade of the invention, there is provided on the holder 1^a a loop or bulb 1^b 30 which firmly secures and holds by pressure and friction a pivot 11^a with which the arms of the clasp 2^a are engaged either in a detachable or permanent fashion. In the larger 35 grades of the tool, there is preferably provided a lever 14 which is pivoted on the female screw 3 and is adapted to be folded into alinement with the holder when the parts are closed or to be swung laterally when one of the tools is extended for use

to enable the user to obtain a better grasp 40 or leverage in manipulating the tool.

Having thus described my invention, what I claim as new and desire to secure by Letters Patent, is:—

1. In a folding tool, the combination with 45 a holder made from a single piece of metal rebent upon itself, of a pivot received in the loop or bend of said holder and having gudgeons at its ends projecting beyond the sides of said holder, means for retaining 50 said pivot in said loop, a tool pivoted between the members of said holder and adapted to be retracted between the same or to be projected therefrom, and a clasp having resilient arms provided with apertures 55 sprung over the gudgeons on the aforesaid pivot, and having its free part adapted to embrace the holder and the shank of the tool in order to secure said tool in either projected or retracted positions. 60

2. In a folding tool, the combination with a handle or holder made of a single piece of metal rebent upon itself, of a tool carried by the holder and adapted for retraction 65 between the members thereof or projection therefrom, a pivot received in the loop or bend of the holder and having gudgeons at its ends, a projection on the holder-engaging said pivot, and a clasp pivotally connected to said gudgeons and adapted to 70 embrace the holder to lock the tool in retracted or projected positions.

In testimony whereof, I hereunto affix my signature in presence of two witnesses.

WEBSTER L. MARBLE.
